(57) **CLAIM**

The ornamental design for a bracket with upper extension for holding a user receiving device, as shown and described.

DESCRIPTION

FIG. 1 is a perspective view of a bracket with upper extension for holding a user receiving device;
 FIG. 2 is a top elevational view thereof;
 FIG. 3 is a front elevational view thereof;
 FIG. 4 is a bottom side elevational view thereof;
 FIG. 5 is a back side elevational view thereof;
 FIG. 6 is a right elevational view thereof; and,
 FIG. 7 is a left elevational view thereof.
 The broken line showing is for illustrative purposes only and forms no part of the invention.
